Primary Examiner — Darlington Ly*Assistant Examiner* — D. Ryan Tisdale(74) *Attorney, Agent, or Firm* — WHDA, LLP(57) **CLAIM**

The ornamental design for a front bumper for automobile as shown and described.

DESCRIPTION

FIG. 1 is a front and left perspective view of a front bumper for automobile, showing my new design;

FIG. 2 is a rear and right perspective view thereof;

FIG. 3 is a front elevation view thereof;

FIG. 4 is a rear elevation view thereof;

FIG. 5 is a left side elevation view thereof;

FIG. 6 is a right side elevation view thereof.

FIG. 7 is a top plan view thereof; and,

FIG. 8 is a bottom plan view thereof.

The ghosted or low contrasted portions of the front bumper for automobile illustrate portions that form no part of the claimed design.

1 Claim, 8 Drawing Sheets(56)
